CLAIM

The ornamental design for a cover for a compartment of a shoe sole, as shown and described.

DESCRIPTION

FIG. 1 is a front perspective view of a cover for a compartment within a shoe sole, showing my new design;

FIG. 2 is a right side elevation view thereof;

FIG. 3 is a front elevation view thereof;

FIG. 4 is a top plan view thereof;

FIG. 5 is a left side elevation view thereof, as viewed along line 5-5 of FIG. 3, with portions of the disclaimed shoe not shown for clarity;

FIG. 6 is a bottom plan view thereof, as viewed along line 6-6 of FIG. 3, with portions of the disclaimed shoe not shown for clarity; and,

FIG. 7 is a front perspective view of the cover for a compartment within a shoe sole, shown in a used condition. The equally sized broken lines illustrating the shoe depicts environmental subject matter that forms no part of the claimed design, while the remaining equally sized broken lines shown in FIG. 7 depict portions of the cover for a compartment of a shoe sole that form no part of the claimed design.

The alternating sized broken lines depict the bounds of the cover for a compartment of a shoe sole that form no part of the claimed design.
